HAROLD BATCHELOR, OF JERSEY CITY, NEW JERSEY, ASSIGNOR TO ALBERT J. STERLING, OF NEW YORK, N. Y.

CLOSURE FOR CONTAINERS.

Application filed May 23, 1925. Serial No. 32,264.

This invention relates to closures for containers and has particular reference to improvements in closures of the general type shown and described in United States application Serial No. 737,973, filed September 16, 1924, by the present applicant.

One of the objects of the present invention is to provide a closure intended primarily for use in sealing containers for highly charged liquids, gases, or liquids in which gas may be generated, or other contents where a powerful seal must be effected and maintained indefinitely, although incidentally the improved closure may be used or adapted for use on containers where the requirements are not so severe.

Another of the objects of the invention is to provide a construction whereby in manufacturing closure caps for a user they may be readily adapted to his particular requirements. Some users may have a product requiring only a light sealing pressure of the closure against the mouth of the container, while others may have a product requiring a very high degree of such pressure to prevent the escape of gases or liquids having an oily content or which are, for another example, highly volatile and exert great outward pressures on the closures, particularly where the bottles or other containers are or may be stored in a warm room. This variation according to the intended use is preferably effected by relieving tension or cutting away the material of the closure at various points to provide a plurality of yielding (preferably resiliently yielding) portions in the closure cap. Among the advantages of this feature is the fact that a standard closure cap may be manufactured and kept in stock and then the caps necessary to supply a user adapted to his particular requirements, particularly where the size of the order does not justify making a special set of tools.

Incidentally the invention embodies the same idea of shortening the skirt of the closure cap after it is in position on the container as was disclosed in the application above referred to, so that the present cap may be adjusted to insure a perfect seal or increase the tension between the closure and the mouth of the container, either as an additional precaution or to effect a more powerful seal than that resulting from the capsing operation. This adjustment may, as

hereinafter made clear, be effected either before or after the cap is in position on the container.

The invention is hereinafter described in detail with reference to the accompanying drawings, but it is to be understood that it is not the desire to be limited to such details except as they are included in the appended claims.

In the drawings, Fig. 1 is a top plan view, Fig. 2 is a bottom plan view, and Fig. 3 is a side view (partly broken away), of one form of the improved closure cap.

Fig. 4 is a top view of a container to which the improved cap may be applied.

Fig. 5 is a partial side view of the container shown in Fig. 4 with one of the novel caps applied, the cap being shown in section along the line 5-5 of Fig. 1.

Fig. 6 is a side view of another and preferred form of the cap.

Fig. 7 is a side view of a modified form of the invention.

Fig. 8 shows another modification which may be used under certain circumstances as hereinafter explained.

In the accompanying drawing there is shown (Figs. 4 and 5) a container to which closure caps embodying the novel ideas may be applied. On the outer periphery of the neck of the container is a set of projections 10 having their lower faces 11 shaped or inclined to serve as cams. If the containers are of glass or other fragile material, the projections 10 may, if desired, have their upper surfaces sloped upward and inward as shown at 12 (Fig. 5) so as to strengthen or give a backing for the projection, thereby giving a sturdy construction which will stand considerable strain. One or more of the projections may be so constructed as to provide a stop 13 which is referred to more in detail later on.

All of the closure caps shown in the drawings are provided with substantially the same form of lug for cooperation with the cam faces 11 on the container. These lugs are preferably formed by shearing or slitting the material of the skirt along short lines 14 (Figs. 3, 6, 7 and 8) in peripheral alignment around the skirt 15 of the cap, the lengths of the cuts or shearings depending upon the size of the lug desired.

The material below the shearing 14 is then formed inward as at 16 (see also Fig. 5) so as to give a concavity gradually increasing in depth from the bottom toward the top of 5 the concavity, thereby providing a very sturdy, inwardly extending, self-reinforced lug, the face or edge 17 (Fig. 5) of which is adapted to engage one of the cam faces 11 on the container. Lugs constructed in the 10 manner shown and described are obviously capable of resisting very considerable strains effected by the coaction of the lugs with the cam faces 11 as hereinafter described. This is particularly true because of the fact that 15 the resilient material employed will not collapse under strain and because of the fact that each lug is well above the lower line of the skirt and is held up to its work by the material of the skirt. The term self-reinforced is, for want of a better term, used 20 in this specification and in the claims to describe this lug construction and to distinguish it from prior structures in which the lug is held up to its work by a reinforcing or stiffening surface or rib on the container. 25

While in the immediately foregoing the shearing along the lines 14 and the forming of the metal below the shearing to produce a self-reinforced lug have been spoken of as 30 separate and successive operations, it is obvious that both operations may be combined in one by the use of suitable shearing and forming tools.

The closure cap shown in Fig. 8 is, like 35 the other forms described later on, preferably made of material which is resilient but which is capable of being given different permanent sets when the elastic limit is exceeded. This permits forming the material in manufacture and later to effect adjustments while retaining the resilient or spring properties of the metal. The cap shown in Fig. 8 has a bead 20 formed so that portions of its upper and lower walls 40 are substantially parallel or at substantially right angles to the axis of the cap, thereby giving a bead which may readily be engaged by pliers or a set of dies operable to force the upper and lower walls of the bead one 45 toward the other, thereby closing up the bead or, in effect, shortening the distance between the lugs 16 and the top 21 of the closure cap. Within the top of the cap is a disk or insert of cork or any other suitable material such 50 as shown at 22 in Figs. 3 and 5.

The bead 20 of the cap shown in Fig. 8 is knurled or corrugated so as to permit a firm grasp or engagement by a tool such as the chuck of a capping machine. In applying the cap to a container, the cap is placed over the mouth of the container in such a way that the lugs 16 will pass between the projections 10. The cap is then rotated preferably until one of the lugs engages with the stop 13, thereby causing the

lugs 16 to act against the cam faces 11 on the projections 10 to pull the closure into engagement with the mouth of the container. The strength of this pull depends upon the distance or length of the relative vertical 70 movement of the cap and container effected by the cooperation of the lugs 16 and cam faces 11 during the rotation of the cap. The bead 20 will permit a slight resilient vertical 75 expansion of the cap, but the degree of expansion is small. After the cap is put in position as just described, the bead 20 may be compressed to bring the top of the closure into firmer engagement with the mouth of the container. From the foregoing it will 80 be seen that the cap shown in Fig. 8 is suitable for use in effecting a highly satisfactory seal, particularly when the lugs 16 and cam faces 11 are substantially uniform in 85 construction and cooperation.

It has been found, however, that it is advisable to provide a more yielding structure than is shown in Fig. 8, preferably one in which resiliency of the material can be used to effect and maintain a seal even though 90 there are variations and irregularities in the cooperating parts of the closure and the container. In the form shown in Fig. 7 the annular portion of the skirt of the cap above the lugs 16 is provided with helical 95 slots 24 and the bead 20 is corrugated or knurled so that it may be firmly grasped by hand or chuck. The lugs 16 are caused to cooperate with the cam faces 11 as before described, but in doing this the torsional 100 stress applied to the bead 20 may cause a slight resilient yielding of the upper part of the cap relative to the lower part thereof, the sections of the skirt between the slots 24 having somewhat the function of strong 105 springs. When the application of rotating force to the bead 20 is discontinued these sections tend to return to their first positions, thereby adjusting the insert 22 to the mouth 110 of the container and insuring a perfect and very strong seal. The number of the helical 115 slots 24 may be varied according to the sealing tension required. The bead 20 in this form of cap is also constructed so that it may be compressed at one or more points to perfect or increase the efficiency of the seal.

The form of cap shown in Figs. 1, 2 and 3 employs the same self-reinforced lugs 16 as previously described and has the same bead 20 suitably constructed for engagement 120 by tools for closing up the bead to, in effect, shorten the skirt or the distance between the lugs 16 and the top of the cap. However, instead of using the helical slots 24 such as shown in Fig. 7, the form of cap now being 125 described has a plurality of slots 25 extending vertically through the bead, thereby dividing the bead into a plurality of separate portions capable of yielding more or less independently of one another when the sealing 130

stress is applied by rotating the cap with its lugs 16 in engagement with the cam faces 11 on the container. This separate or independent yielding affords a suitable way of compensating for minor irregularities. For example, if the mouth of the container should slant slightly the sections of the bead between the slots 25 would yield more at one side than the sections at the other side, thereby causing a slight tilt of the top of the cap and bringing the seal into firm and uniform engagement with the mouth of the container. The number of slots 25 may be varied according to the requirements as to stiffness or resiliency. If suitable material is used the sections of the bead between the slots therein form substantially a peripheral or annular series of springs.

The form of cap shown in Fig. 6 is preferred. It has the same bead 20 as the other forms and is used for the same purposes. The bead has vertical slots 27 dividing the bead into separate yielding sections for the same purpose as previously pointed out. In the preferred form these separate portions are made even more independent in their operation, by peripheral slots connecting certain of the vertical slots. It has been found best to make these peripheral slots in the form of knife cuts just below the bead, although in Fig. 6 they are shown at slightly below the bead. This showing is, however, for the sake of clearness by preventing confusion with the shading of the lower part of the bead. It is obvious, of course, that much the same result can be accomplished by making the peripheral slots in the bead itself or at any point where they will connect two or more of the adjacent vertical slots.

In manufacturing the caps they may all be manufactured uniformly like the one shown in Fig. 8, or the operations carried as far as shown in Figs. 1, 2 and 3. Either of these two forms will have quite a wide range of usefulness. Then the peripheral slots 28 may be put in, the number of such slots 28 varying according to the use to which the caps are to be put. Preferably both the vertical slots 27 and the peripheral slots 28 are made with the specific use in view, the number of such slots varying with the pressure which it is necessary to apply against the container mouth.

In addition to this flexibility with reference to the number and positions of the slots, the bead 20 gives an additional means for adapting a stock cap to specific uses. While, as before stated in this application and as explained more fully in the previous application above mentioned, the bead may be operated upon after the cap is in position on the container, the compression of the bead may be partially effected in all of a lot of caps before they are applied to containers

where it is desired to increase the sealing tension or shorten the skirts to compensate for a change in the distance from the effective faces of the cams 11 and the top of the container mouth. A corresponding increase in the distances between the cam faces and the top of the container may be compensated for by an expansion or partial opening of the bead to lengthen the skirt, although this cannot be carried to such an extent as to interfere with proper engagement of the bead by tools for compressing the bead after the closures are in sealing position.

If desired, the reinforced lugs 16 in the closure caps may be so formed that one side of one or all of the lugs will be substantially on a radius of the cap, thereby forming a more or less abrupt stop to cooperate with the stop 13 on the container.

What is claimed is:

1. The combination with a container provided with a plurality of projections around its mouth having their lower faces formed as cams, of a closure cap of resilient material including a skirt having a portion thereof constructed to provide an annular series of springs, and a plurality of self-reinforced lugs formed in the skirt below the series of springs and wholly above the lower edge of the skirt for engaging the aforesaid cam faces.

2. The combination with a container provided with a plurality of projections around its mouth the lower faces of which are formed to serve as cams, of a closure cap of resilient material including a skirt provided with an annular bead slotted vertically to divide the bead into separate resiliently yielding portions and a plurality of slots extending in an annular direction and connecting certain of the vertical slots, and a plurality of self-reinforced lugs below the resiliently yielding portions constructed substantially as described for cooperation with the aforesaid cam faces.

3. The combination with a container having a plurality of projections around its mouth the lower faces of which are constructed to serve as cams, of a closure cap of resilient material including a skirt having self-reinforcing lugs in its periphery constructed substantially as described for cooperating with the aforesaid cam faces, and an annular bead above said lugs and below the top of the skirt constructed to yield resiliently when the cap is rotated with the lugs therein in cooperating relation with the cam faces.

4. The method of manufacturing closure caps for sealing containers for various materials requiring varying degrees of sealing tension, which comprises forming each cap from resilient material and forming self-reinforced lugs in the lower portion of the skirt for cooperating with the projections

around the mouths of the containers, forming a peripheral bead in the skirt above the lugs in such manner that the bead may resiliently expand as the lugs on the skirt are brought into sealing cooperation with the container projections, said bead also being made to project far enough to be readily

engaged by a tool for closing up the bead to tighten the seal, and slitting the skirt above the lugs to form any desired number 10 of yielding portions in the skirt.

In testimony whereof I hereto affix my signature.

HAROLD BATCHELOR.
